UNITED STATES PATENT OFFICE.

WILLIS S. SHERMAN, OF MILWAUKEE, WISCONSIN, ASSIGNOR TO SIGHT FEED OIL PUMP COMPANY, OF MILWAUKEE, WISCONSIN, A CORPORATION OF WISCONSIN.

OIL-PUMP MOTOR.

No. 821,195.

Specification of Letters Patent.

Patented May 22, 1906.

Application filed February 20, 1904. Serial No. 194,517.

To all whom it may concern:

Be it known that I, WILLIS S. SHERMAN, residing in Milwaukee, in the county of Milwaukee and State of Wisconsin, have invented 5 a new and useful Improvement in Oil-Pump Motors, of which the following is a description, reference being had to the accompanying drawing, which is a part of this specification.

10 This invention relates particularly to certain new and useful improvements in oil-pump motors, but broadly covers improvements in motors for any purpose, and has for its object to provide operating means having 15 movable support from a moving body and capable of imparting motion to an operated means by reason of the difference in the effect produced by the movements of the body on the support and on the operating means, 20 such difference in effect being due to the inertia of the operating means.

Another object of this invention is to provide a moving body carrying an actuating means mounted to be movable with relation 25 to the moving body and means connecting the body and the said actuating means adapted to receive motion as the result of the inertia of the actuating means during the movements of the body.

30 Another object of this invention is to provide a machine, oil-feed pump, or the like with an automatic operating means adapted to impart motion to such oil-feed pump or similar device during the movements of the 35 machine only and receiving its impulse from such movements of the machine.

A further object of this invention is to accomplish the above results by means of a 40 movable weight the inertia of which renders it less susceptible to the influence of the movements of the machine than its support and the difference in the effects produced by such movements on the weight and on its support being utilized to operate the pump.

45 Another object of this invention is to vary the degree of effect produced by the motor, as by rendering the weight adjustable upon its lever-arm to increase or diminish the ex-

tent of movement thereof, and, again, by providing adjustable stops to limit the movements of the lever-arm. 50

With the above primary and other incidental objects in view the invention consists of the devices and parts and their equivalents, as hereinafter set forth. 55

In the accompanying drawing the figure represents a side elevation of an oil-pump motor embodying the principles of this invention and applied to a sight-feed oil-pump, such as is shown and described in Letters 60 Patent to Wilber E. Richardson, No. 661,323, dated November 6, 1900.

In the drawing, 1 represents the oil-pump, which may be of any desirable type and which is bolted or otherwise rigidly secured 65 to a supporting means 2, such as the cab of a locomotive or any other body, preferably receiving motion from the mechanism supplied with oil by the pump, and 3 is the shaft of said oil-pump, which is capable of operating 70 the pump mechanism when given slight oscillations. A sleeve 4 is fixed on the shaft 3 and held rigid therewith by means of the nut 5, threaded on said shaft, and preferably binding the sleeve upon a shouldered squared 75 portion of the shaft. A socket 6 is provided on said sleeve, in which a lever-arm 7 is secured in any suitable manner.

A weight, preferably a ball of solid metal with a central bore therethrough having a 80 sliding fit upon the lever-arm 7, is adjustably mounted on the lever-arm 7 and held in its adjusted position by a set-screw 9, threaded through a collar 10, which is formed with or attached to the ball-weight 8, said set-screw 85 being adapted to engage the lever-arm 7.

On each side of the socket 6 is rigidly mounted a leaf-spring 11, secured thereto in any suitable manner, such as by screws 12, and these leaf-springs extend upwardly and 90 curve outwardly and their ends are slightly turned back and are adapted to engage with the inner ends of set-screws 13, threaded through the opposite laterally-extending lugs 14 of a bracket 15, which is bolted to the top 95 of the pump 1 or rigidly mounted in any

other desirable manner. The projecting lugs 14 of the bracket 15 stand in the path of the lever-arm 7 and are only prevented from being engaged by said lever-arm by reason of 5 the engagement of the yielding cushioning springs 11, engaging with the set-screws 13, which are bound in their adjustments by jam-nuts 16, turned against the outside of the lugs 14.

- 10 In operation while the supporting means 2 is making quick horizontal motions, such as are common with a locomotive-cab when under way, the inertia of the ball-weight 8 tends to prevent its participating in such 15 movements, and as the pump and therefore the shaft 3 take the movement of the support the result is that said weight is caused to oscillate with respect to its support. When the weight is in either of its extreme positions—as, for instance, the position shown in the drawing—and the movable support 2 is given a quick motion—say to the left—the tendency of the ball-weight 8 to remain in the position shown causes the shaft 3 to pass 20 therebeneath, so that the center of gravity of the weight is then on the other side of the vertical plane of the shaft 3 to that as shown, when gravity will cause said weight to swing forcibly to the right and engage the right-hand spring 11, with the set-screw 13, until the 25 said spring is bent to a considerable extent. When the compression of the spring 11 stops the swing of the ball-weight, it exerts its pressure to return the ball-weight 8 to its original position, and if it succeeds in carrying 30 it beyond the vertical plane of the shaft 3 the motion is continued on the other side of the vertical plane of shaft 3 and the same action takes place with the other spring 11. 35 The springs 11 serve the double purpose of limiting the swing of the weight 8 and also causing it to rebound and aid the movements of the support in keeping up the motions of the weight, so as to continue the operation of 40 the pump as long as the motions of the support continue. When it is found that the motions of the support 2 are not sufficient to carry the weight over the vertical plane of the shaft 3, and consequently the pumping 45 operation is not properly effected, the ball-weight 8 is lowered upon the lever-arm 7, so that it has less distance to travel in reaching said vertical plane of the shaft 3, and consequently the slight movements of the support 50 2 which were formerly insufficient to carry the weight the required distance are now capable of successful operation. Furthermore, the degree of swing of the lever-arm 7 may be varied to some extent by the adjustment of the set-screws 13 to effect this result; 55 but the prime object of these set-screws is to

equalize the conditions on both sides of the lever-arm 7 as much as possible, so that no greater influence is necessary to move the weight in one direction than is capable of 65 moving it in the opposite direction.

The device, as above described, is preferably arranged in a locomotive-cab in such a manner as to have the plane of movement of the lever-arm 7 transverse of the direction of 70 travel of the locomotive, so that the lateral motions of the cab will effect the operation of the motor.

It is obvious that satisfactory results may be accomplished by inverting the lever-arm 75 7, so that the weight 8 hangs below the shaft 3, and in such construction the springs and stops may or may not be dispensed with.

While the part 2 has been referred to herein as the "movable support," it is obvious 80 that the pump 1, which is intended to have a rigid connection therewith, and so partake of the movements thereof, may be considered as a movable support, and it is with the understanding that this term "movable support" 85 is sufficiently broad to cover any body or support capable of movement or designed to receive movement that such term is employed in the following claims. Such term is not intended to render the combinations 90 incomplete without the presence of a moving engine-cab or other body by which the parts may be carried.

What I claim as my invention is—

1. A movable support, a lever-arm suitably 95 pivoted thereto, a weight on the lever-arm, springs carried by the lever-arm, a bracket rigidly connected with the support and having laterally-extending lugs, and set-screws threaded through the lugs with binding-nuts 100 to lock them in their adjustments, said springs being adapted to engage the set-screws to cushion the movements of the lever-arm.

2. A movable support, a shaft journaled thereon, an upwardly-extending lever-arm 105 carried by the shaft, a weight on the lever-arm, a bracket rigidly connected with the support, laterally-projecting lugs on the bracket, set-screws with binding-nuts threaded through the nuts, and leaf-springs 110 secured to the lever-arm and adapted to engage the set-screws to cushion the swing of the lever-arm and start its return movement.

3. In combination with an oil-pump having an oscillating shaft, a sleeve secured on the shaft, a lever-arm mounted in the sleeve and extending upwardly, a weight adjustably mounted on the lever-arm so as to be movable nearer to or farther from the shaft, leaf-springs mounted on the sleeve and bending away from the lever-arm, a bracket rigidly mounted on the pump and having arms 115 120

standing in the path of movement of the lever-arm, and set-screws adjustably threaded in the arms of the bracket to be engaged by the leaf-springs and having jam-nuts threaded thereon to hold them in their adjustments.

5. 4. In combination with an oil-pump having an oscillating shaft, a lever-arm secured to the shaft and extending upwardly, a weight mounted on the lever-arm, a bracket
10 secured to the pump with outstanding arms

in the path of movement of the lever-arm, and set-screws adjustably threaded through said arms adapted to vary the arc of movement of the weight.

In testimony whereof I affix my signature ¹⁵ in presence of two witnesses.

WILLIS S. SHERMAN.
